UNITED STATES PATENT OFFICE.

NATHANIEL O. GOLDSMITH, OF CINCINNATI, OHIO, ASSIGNOR TO THE WEIR FROG COMPANY, OF SAME PLACE.

STREET-RAILWAY SWITCH.

SPECIFICATION forming part of Letters Patent No. 398,248, dated February 19, 1889.

Application filed May 24, 1888. Serial No. 274,921. (No model.)

To all whom it may concern:

Be it known that I, NATHANIEL O. GOLDSMITH, of Cincinnati, in the county of Hamilton and State of Ohio, have invented certain new and useful Improvements in Street-Railway Switches, of which the following is a specification.

The object of my invention is to provide a cheap and durable switch for girder-rails. 10 The various features of my invention will be fully set forth in the description of the accompanying drawings, making a part of this specification, in which—

Figure 1 is a top plan view of my improvement. Fig. 2 is a section on line xx , Fig. 1. Fig. 3 is a section on line yy , Fig. 1. Fig. 4 is a section on line zz , Fig. 1. Fig. 5 is a section on line ss , Fig. 1. Fig. 6 is a modification showing a rivet-tongue.

20 I have shown my invention here as adapted to be used either with a stationary or movable tongue-switch.

A represents a girder-rail, preferably a center girder-rail, having the two trans-flanges a e ; but the flange a may be omitted, if desired. This girder-rail A is beveled at its flange-head and web to form a switch-point of the desired angle.

The switch-rail is shown as constructed of 30 two T-irons, B C, the T-iron C resting upon the same base as the girder-rail A and forming a bearing for the web b of the T-iron B, which is placed at right angles to the T-iron C, the web of the T-iron B resting upon web 35 of the T-iron C. In order to hold these two T-irons in position, I have provided angle-irons 1, fitting the webs b c of the iron B C and secured by rivets 2 3. These are beveled to fit the girder-rails.

40 4 represents a built-up head, which is shown secured to the web b by rivets 5 5, Fig. 1.

6 represents a tongue, which is pivoted to the T-rails by means of center bolt, 7, passing down through the flange and secured by nut or key 8.

9 represents a filling-block between the T-iron C and the girder-rail A, through which passes the center bolt, 7, and the transverse

horizontal bolts 10, firmly securing the parts 50 together.

11 represents similar filling-blocks placed forward of the tongue 6, for securing the front portion of said switch-points.

12 represents filling-blocks on the opposite 55 side of the T-iron C. These blocks are preferably made of cast-iron of the shape to fit the flanges of the said T-irons at one side and the T-iron and girder-rail on the other side, and the said parts are secured together by means 60 of through-bolts 13.

In Fig. 6 I have shown a modification which represents the tongue or built-up head 4 projecting forward and forming a rigid tongue, which is preferably used on the switch-mate. 65 It will be obvious that the T-iron B performs two offices. The web A is sufficiently long to form space between the flange s and the head of the rail to allow the tongue 6 to move. It also performs the office of a guard-rail for the 70 flanges of the wheel.

Having described my invention, what I claim is—

1. A side guard-rail for a switch, composed of the irons B C, bolted together and 75 to the girder-rail A, substantially as herein set forth.

2. In combination with the girder-rail A and switch-rail formed of the T-irons B C, the filling-blocks 11 12, and the through-bolts 13, 80 for securing the said parts together, substantially as herein specified.

3. The combination, with the girder-rail A, of the switch-rail B C, built-up head 4, and the angle-arm 1, for joining the said parts together, substantially as specified.

4. In a switch-point, the guide-rail composed of the T-irons B and C, having their webs placed at right angles to each other, and the flange forming the guard-rail, and the 85 flange b , forming the base for the built-up rail 4, substantially as herein specified.

5. In a switch, the guard-rail composed of the T-irons B and C, secured together by means of the angle-iron 1, bolted to webs, filling-block 12, and the flange s , forming a guard for the tongue-rail 6, substantially as herein specified.

6. A switch-rail composed, substantially, of the T-irons B and C, placed at right angles to each other, the web of the iron B resting upon the web of the T-iron C, and secured 5 together by angle-plates 1 and rivets and bolts and united to said girder-rails by filling-blocks and bolts, substantially as herein specified.

In testimony whereof I have hereunto set my hand.

NATHANIEL O. GOLDSMITH.
